UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMINGTON, PENNSYLVANIA, A CORPORATION OF PENNSYLVANIA.

PROTECTOR FOR CONTACT-FINGERS.

1,318,244.

Specification of Letters Patent.

Patented Oct. 7, 1919.

Application filed September 10, 1917. Serial No. 190,511.

To all whom it may concern:

Be it known that I, WALTER V. TURNER, a citizen of the United States, residing at Wilkinsburg, in the county of Allegheny and 5 State of Pennsylvania, have invented new and useful Improvements in Protectors for Contact-Fingers, of which the following is a specification.

This invention relates to hand operated 10 electric controllers and has for its principal object to provide means for protecting the contact fingers.

It sometimes happens that the contact fingers of a controller are bent out of position 15 by an unskilled operator, so that the finger may not make contact in the position intended.

In order to prevent this, it is proposed to incase each finger in such a manner that the 20 finger will be inaccessible for bending so far as the ordinary operator on the road is concerned.

In the accompanying drawing; Figure 1 25 is a transverse section of an electric controller, showing the finger protecting device applied; Fig. 2 a face view of the protecting device; Fig. 3 a side elevation thereof; and Fig. 4 a plan view.

As shown in the drawing, the protecting 30 device may comprise a casing 1 having a base 2 for securing same to the insulation block 3 in the controller casing 4.

Within the casing 1 is mounted the usual 35 contact finger 5 adapted to engage the usual contacts 6 of the controller drum.

The protecting casing incloses the finger on all sides, but has an opening 7 through

which the contact finger projects, so as to engage the drum contacts.

In order to still further prevent the possible excessive bending of the finger, the finger may be provided with a projection 8 which engages the inner wall of the casing when it is attempted to bend the finger outwardly.

Having now described my invention, what I claim as new and desire to secure by Letters Patent, is:

1. The combination with an electric controller having a contact finger, of a casing 50 mounted within the controller and separately inclosing said contact finger and having an opening through which the finger projects.

2. The combination with an electric controller having a contact finger, of an individual casing mounted within the controller for separately inclosing only the contact finger and provided with an opening of limited extent through which the contact finger is adapted to make contact.

3. The combination with an electric controller having a contact finger, of a casing hood mounted in the controller and locally inclosing the contact and having a restricted opening through which a portion of the contact finger projects, said contact finger having an extended portion for engaging the walls of the hood and thereby limiting the outward movement of the finger through said opening.

In testimony whereof I have hereunto set my hand.

WALTER V. TURNER.
